SANDER-POLISHER

Melvin H. Boldt, Glenview, Ill., assignor to G. W. Murphy Industries, Inc., Houston, Tex., a corporation of Texas

Filed Jan. 23, 1969, Ser. No. 15,477

Term of patent 14 years

Int. Cl. D8—02

U.S. Cl. D8—62

FIG. 1 is a perspective view of a sander-polisher, showing my new design;

FIG. 2 is a left side elevational view of the sander-polisher illustrated in FIG. 1;

FIG. 3 is a right side elevational view of the sander-polisher illustrated in FIG. 1;

FIG. 4 is a top plan view of the sander-polisher illustrated in FIG. 1;

FIG. 5 is a front elevational view of the sander-polisher illustrated in FIG. 1;

FIG. 6 is a rear elevational view of the sander-polisher illustrated in FIG. 1; and

FIG. 7 is a bottom plan view of the sander-polisher illustrated in FIG. 1.

The dominant features of my design reside in the portions shown in full lines.

I claim:

The ornamental design for a sander-polisher, as shown and described,
